By his Attorneys,

N. M. Worley Inventor

UNITED STATES PATENT OFFICE

NATHAN M. WORLEY, OF VICTOR, COLORADO.

BOUQUET-HOLDER.

SPECIFICATION forming part of Letters Patent No. 634,517, dated October 10, 1899.

Application filed July 10, 1899. Serial No. 723,364. (No model.)

To all whom it may concern:

Be it known that I, NATHAN M. WORLEY, a citizen of the United States, residing at Victor, in the county of Teller and State of Colorado, have invented a new and useful Bouquet-Holder, of which the following is a specification.

This invention relates to bouquet-holders of that class which are adapted to be fastened to the lapel of a coat or other part of the clothing, and has for its object to provide improved means for supporting the bouquet in the holder, which will permit of the ready insertion and removal of the bouquet.

To these ends the present invention consists in the combination and arrangement of parts, as will be hereinafter more fully described, shown in the accompanying drawings, and particularly pointed out in the appended claims, it being understood that changes in the form, proportion, size, and the minor details of construction may be made within the scope of the appended claims without departing from the spirit or sacrificing any of the advantages of the present invention.

In the drawings, Figure 1 is a perspective view of the improved bouquet-holder. Fig. 2 is a longitudinal sectional view thereof. Fig. 3 is a detail perspective view of the spring-clamp for supporting the bouquet upon the holder. Fig. 4 is an enlarged transverse sectional view taken on the line $x-x$ of Fig. 2.

Corresponding parts in the several figures of the drawings are designated by like characters of reference.

Referring to the accompanying drawings, 1 designates the body of the holder and is of substantially conical form, having the apex 40 or pointed end normally extending downward. The back 2 of the holder is preferably flattened, as best shown in Fig. 4, extended above the top of the body, as at 3, and provided with opposite side flanges 4, which are continuations of the sides of the body, but are narrower than the latter. Near the upper end of the back there is provided an inwardly disposed depression 5, which forms a transverse stop-shoulder 6. Connected to the back 50 of the holder is a substantially L-shaped stick-pin 7, having the end of its transverse

head 8 soldered or otherwise connected to the depressed portion of the back and against the stop-shoulder 6, thereby forming a rigid and durable connection between the pin and 55 the body of the holder.

Located within the holder is a spring-clamp 9, formed from a single blank of spring metal and comprising a substantially straight shank having a transverse jaw 10 at its upper end. 60 The lower end of the shank extends through a suitable opening formed in the lower pointed end of the body and is provided with a transverse bend or flange 11, which engages across the outer lower end of the body and serves to 65 hold the shank in position. The transverse jaw 10 normally rests against the front edges of the flanges 4, adjacent to the upper edge of the body, and projects at opposite sides of said flanges, so as to afford a finger-piece for 70 the operation of the spring-clamp.

To apply the bouquet to the holder the opposite transverse edges of the jaw 10 are held between the thumb and forefinger and moved outwardly away from the flanges 4, after which the stem of the bouquet is inserted into the body of the holder between the spring-clamp and the back 2, after which the jaw is released and the latter springs into engagement with the stems of the flowers and clamps the 80 same between the back of the holder and the opposite flanges 4.

From the foregoing description it will be apparent that the present device provides an exceedingly strong and durable bouquet- 85 holder, as the spring-clamp is the only movable part thereof and is effectively housed by the body of the holder, and thereby protected against being accidentally broken or displaced.

What I claim is—

1. A bouquet-holder, comprising a hollow body having an open upper end, and a spring-clamp housed within the body and having its free end projecting outwardly beyond the 95 open end of the body, substantially as shown and described.

2. A bouquet-holder, comprising a hollow body having an open upper end, and provided with an extension projecting beyond 100 the open end thereof, and a spring-clamp housed within the body, and having its free

end projecting outwardly beyond the open end thereof and engaging with the extension, substantially as shown and described.

3. A bouquet-holder, comprising a hollow body having an open upper end, an extension projecting beyond the open end of the body and provided with opposite longitudinal flanges, and a spring-clamp housed within the body, the free end of the clamp projecting outwardly beyond the open end of the body and provided with a transverse jaw engaging with the opposite flanges, substantially as shown and described.

4. A bouquet-holder, comprising a hollow body having an open upper end, an extension projecting beyond the open end of the body, and provided with opposite longitudinal flanges, and a spring-clamp housed within the body, the free end of the clamp projecting outwardly beyond the open end of the body, and provided with a transverse jaw projecting at opposite sides of the clamp and also extending laterally beyond the opposite flanges, substantially as and for the purpose set forth.

5. A bouquet-holder, comprising a hollow body having an opening formed through the lower end thereof, and a spring-clamp, having a shank housed within the body, the lower end of the shank projecting through the opening in the body, and provided with a transverse bend or flange engaging across said lower end, substantially as shown and described.

6. A bouquet-holder, comprising a body having a transverse shoulder provided upon the back thereof, and a substantially L-shaped stick-pin having the free end of its transverse head connected to the back and against the shoulder thereof, substantially as shown and described.

In testimony that I claim the foregoing as my own I have hereto affixed my signature in the presence of two witnesses.

NATHAN M. WORLEY.
